(57) **CLAIM**

The ornamental design for a fabric as shown, and described.

DESCRIPTION

FIG. 1 is a top perspective view of a fabric in accordance with the present invention.

FIG. 2 is a top plan view of the fabric of FIG. 1.

FIG. 3 is a bottom plan view of the fabric of FIG. 1.

FIG. 4 is a front elevation view of the fabric of FIG. 1.

FIG. 5 is a rear elevation view of the fabric of FIG. 1.

FIG. 6 is a right elevation view of the knitted fabric of FIG. 1; and,

FIG. 7 is a left elevation view of the knitted fabric of FIG. 1.

The broken lines in the drawings depict the boundaries of the claim and form no part thereof.
